(57) **CLAIM**

The ornamental design for an electronic device for tracking physical activity, as shown and described.

DESCRIPTION

FIG. 1 is a top side perspective view of the electronic device for tracking physical activity;

FIG. 2 is a left side view thereof;

FIG. 3 is right side view thereof;

FIG. 4 is a bottom view thereof;

FIG. 5 is a top view thereof;

FIG. 6 is an end view of one end thereof; and,

FIG. 7 is an end view of the other end thereof.

The broken lines form no part of the claimed design and the drawings include surface shading that represents contour and not surface ornamentation.
